UNITED STATES PATENT OFFICE.

JOSEPH WHITE, OF PISCATAWAY TOWNSHIP, UNION COUNTY, NEW JERSEY, ASSIGNOR, BY DIRECT AND MESNE ASSIGNMENTS, OF ONE-HALF TO HALL PRINTING PRESS COMPANY, OF DUNELLEN, NEW JERSEY, A CORPORATION OF NEW JERSEY, AND ONE-HALF TO MIEHLE PRINTING PRESS AND MANUFACTURING COMPANY, OF CHICAGO, ILLINOIS, A CORPORATION OF ILLINOIS.

SHEET-REGISTERING MECHANISM.

1,419,595.

Specification of Letters Patent. Patented June 13, 1922.

Application filed August 7, 1912, Serial No. 713,745. Renewed October 1, 1921. Serial No. 504,764.

To all whom it may concern:

Be it known that I, JOSEPH WHITE, a citizen of the United States, residing at Piscataway Township, county of Union, State 5 of New Jersey, have invented certain new and useful Improvements in Sheet-Registering Mechanism; and I do declare the following to be a full, true, and exact description of said invention, such as will enable others skilled in the art to which it 10 appertains to make use of the same.

This invention relates to mechanism for positioning sheets in machines for operating on such sheets, and particularly to devices for positioning the sheets so that they 15 will be printed in accurate register in printing machines, especially in those machines in which the sheets follow each other very closely, so that the time afforded for positioning the sheet is very small. At the same 20 time, this invention permits the greatest accuracy in the registry of sheets, although only the minimum time is taken to obtain such registry. My present invention is intended to position the sheet both laterally 25 and longitudinally, although the mechanisms for side register and front register are more or less independent of each other. My novel mechanism may be used in connection with any form of sheet handling 30 device by which sheets are presented to machines.

In my present invention, I have provided means for first squaring the sheet and giving 35 it a preliminary front registry, then a side registry and then a final front registry. This order, although not absolutely necessary, is advantageous. By squaring the sheet first, the side registry may be made 40 before the front registry and while the sheet is in motion and the final front registry delayed until the sheet is presented to the machine, and preferable without stopping the sheet. I have also provided a 45 mechanism by which the sheet is given a preliminary front registry and a side registry while it is on the run toward the machine, and then is given its final front registry directly on the machine itself, thus eliminating any slip due to the transfer of the 50 sheet from one piece of mechanism in which

it has been registered to another, which has been a difficulty with many other types of quick-acting registry devices.

To insure the greatest accuracy for both 55 front and side registry, I find it desirable to provide mechanism which will square that edge of the sheet on which final registry is dependent, because it is practically impossible to depend on the edges of sheets being 60 parallel, and working first on one edge and then on the opposite edge does not produce the most accurate results. By first squaring the sheet by its registry edge and giving it a preliminary register at the same time, 65 and then giving it a side register, I am enabled to grasp and hold the sheet securely in its side registered position, since in giving the final front registry, the side registry will not be disturbed in any way. The side 70 gage could be removed, if found desirable, after the sheet is thus secured. This would not be the case if the preliminary register were made from the rear edge of the sheet, for in giving the final front registry, the 75 sheet might, and in most cases would, have to be shifted to bring its front edge against the front stops, which would necessitate the sheet being free and would also require a re-registration sidewise after the final front 80 registry.

I have also provided simple and efficient mechanism by which the most accurate register may be obtained without stopping the sheet in its travel from the sheet handling 85 devices into the machine which is to operate on it.

In the drawings, Figure 1 represents a side elevation of my novel positioning devices in connection with so much of a rotary 90 printing press as is required to illustrate the invention, this printing press being merely an illustrative type of the machines to which my present invention may be applied.

Figure 2 is a plan view of Figure 1.

Figure 3 represents an enlarged sectional view of a portion of my invention.

Figure 4 represents the same mechanism as shown in Figure 3 with the parts in different positions.

Figure 5 is a plan view of Figure 4.

Figures 6, 7, 8, and 9 represent my novel side gaging and sheet gripping devices as they would be seen when viewed from the right of Figure 1, Figures 6 and 7 representing the left and right grippers respectively, in their open position, and Figures 8 and 9, the same grippers in their closed position.

Figure 10 is a partial plan view of Figure 3.

The corresponding parts are referred to both in the drawings and the following description by similar reference characters.

Referring now to Figure 1, 9 represents the impression cylinder, and 10 the form cylinder of a printing press, which I have chosen for purposes of illustration. These cylinders, in the type of machine shown, are continuously rotating and are geared together in the usual manner. The cylinder 9 is provided with an impression or sheet carrying surface 11, and with a usual gripper shaft 12 carrying grippers 13, the shaft 12 being operated by the cam roller 14 running on the cam 15 all as in the usual manner. At the front end of the surface 11 is a front gage 16 which is capable of adjustment in relation to the surface 11, being mounted on a slideway, as shown particularly in Figure 3, and held in adjusted position by the screw 17. 18 represents a set of tapes or other sheet carriers running around pulleys 19 and driven thereby, the other end of the tapes extending to the right of Figure 1, to the sheet handling devices from which the sheets are received. A sheet placed on top of these tapes 18 will be carried thereby toward the cylinder 9. The pulleys 19 derive their motion from the cylinder 9 through the intermediate gear 20, engaging with a gear on the shaft 22 on which the pulleys 19 are mounted. As will be seen particularly in Figure 4, in the form of the invention illustrated, the ratio of the gearing is such as to move the tapes 18 toward the cylinder 9 at a speed greater than that of the surface of the cylinder. 23 represents a set of sheet guides spanning the gap between the pulleys 19 and the cylinder 9.

The side frames of the machine are provided with guideways in which is mounted a reciprocating carriage. This carriage is composed of side frames 24, the front shaft 25 and a pair of cross rods 26 fastened therein. Attached to the side frames 24 and running in the grooves in the side frames are a pair of front blocks 27 and a pair of rear blocks 28. Connected to the middle of the rods 26 is a frame 29 to which is pivotally attached a link 30 pivotally connected at 30' to a chain 31 engaging with sprockets 32. Power is given to these sprockets through the shaft 33 driven by the gear 34 through the intermediate gear 35 by the gear 36 on the end of the cylinder 9. In the form of the

invention illustrated, the pitch diameter of the gear 36 is larger than the circumference of the cylinder 9, and therefore the chain 31 has a greater velocity than the surface of the cylinder 9. As will be seen by an inspection of Figure 1, by reason of the connection between the carriage and the chain 31, the carriage is reciprocated back and forth toward the cylinder 9, moving at a constant speed when the connection 30' is travelling between the sprockets 32, and at a variable speed when this connection 30' is moving around the sprockets. In order to relieve the strain on the carriage and its driving mechanism when it is being reversed, I provide dash pots 37—37 of the well known construction, these dash pots being entered by the pistons 38—38 attached to the carriage.

Referring now to Figures 4 and 5, it will be seen that front block 27 is mounted on an eccentric bearing 39' rotating on the stud 39, so that when the bearing 39' is turned, the block 27 will rise and fall in reference to the side frame 24. This eccentric bearing is provided with an arm 40 carrying a cam roller 41, the arm 40 being also provided with a spring 42 acting in the well known manner to hold the arm 40 in the position to which it may be turned. A cam 43, fixed to the side frame of the press, is engaged by the cam roller 41 as the carriage is moved forward and moves the cam roller 41 to the position shown in Figure 4, thus turning the eccentric bearing 39' in the block 27. Since this block 27 cannot itself move downward, being held in the guideways of the side frames of the machine, the side frames 24 of the carriage are raised at the front end. Similar cams 44 are provided at the rear of the machine to engage the cam rollers 41 on the return stroke of the carriage to turn the arm 40 downward and thus lower the front of the side frames 24. By this mechanism, the front end of the side frames 24 travels in one plane as it moves toward the cylinder 9, and is then raised into another plane and returned in this new plane to the original position when it is again depressed.

At the front of the carriage, on the shaft 25, are adjustably mounted a pair of heads 45, each head carrying a front stop 46 adjustable horizontally in the well known manner, as shown particularly in Figure 4, and provided with means to clamp it in adjusted position, also in the well known manner. Mounted in the frames 24 is a shaft 47 which is provided with a pair of wiping arms 48 and with a cam lever 49, carrying a cam roller 50 normally held away from the lever by a spring 51 but so mounted on its stud as to be movable toward the lever, longitudinally of the shaft 47. The roller 50 is arranged to engage with a cam 52 sup-

ported on the side frames of the machine. As shown particularly in Figures 3 and 4, the forward motion of the carriage causes the roller 50 to engage with the lower surface 5 of the cam 52 to rotate the shaft 47 and swing the arms 48 downward. When the roller 50 reaches the end of the cam, the spring 53 swings shaft 47 back again and raises the arms 48. On the return stroke 10 of the carriage, the roller 50 engages with the side of the cam 52 and is pushed back toward the lever 49 against the pressure of the spring 51 to allow the roller to pass the cam 52 without affecting the shaft 47.

Extending between the side frames 24 of the carriage is a square bar 54. On this bar and at the left, as shown particularly in Figure 6, is a slidably mounted block 55, which carries a gage pin 56 and a gripper 15 57 pivoted at 58. Connected to the gripper 57 is a rod 59 carrying a cam roller 60. The rod 59 is provided with a spring 61 arranged to hold the gripper 57 normally open. The block 55 is provided with a gripper surface 20 62 against which the gripper 57 closes and the gripper 57 is provided with a hole 163 to allow the pin 56 to pass therethrough. The block 55 is provided with a cam roller 63 and a spring 64, abutting against a block 25 65 fastened to the bar 54, tends to hold the block 55 normally to the left of Figure 6.

Extending across the side frames of the machine are a pair of bars 66—66 on which is adjustably mounted a cam bar 67, shown 30 particularly in Figure 2. This cam bar is held below the bars 66—66, as shown in Figure 6, and the roller 60 engages with the top of the cam bar 67 while the roller 63 engages with the side thereof.

The side gage and grippers on the other end of the bar 54, shown in Figure 7, is similar in most respects to that on the left side. 68 is the block slidably mounted on the bar 54, 69 is the gage pin, 70 the gripper 40 71 pivoted at 71 on the block 68 and provided with a rod 72 and cam roller 73. The block 68 is also provided with the cam roller 74, the cam rollers 73 and 74 engaging with the cam bar 75 held by the cross bar 66—66, in a 45 manner similar to the cam bar 67. The block 68 is normally held to the left of Figure 7 by the spring 76 pressing against the block 77 fastened to the bar 54.

In order to prevent the edge of the sheet 50 S riding up the front of the gage 16 when pushed thereagainst by the grippers 57 and 70 and the wiper 48, I provide a set of over-guides. In the form illustrated, these over-guides consist of a pair of fingers 78 connected by a common hub and loosely mounted on the shaft 12. The hub of the fingers 78 is provided with an extension 79 carrying a set screw 80 bearing against an arm 81 fastened to the shaft 12. Between 55 this arm 81 and an extension 82 of the fingers 78 is a spring 83. The fingers 78 engage with the pin 84 passing through the gage 16, this pin being set in such a position that the fingers 78 are held normally above the surface 11 of the cylinder 9 to permit the sheet 70 to be passed under the fingers 78 and against the gage 16. The spring connection 83 permits the shaft 12 to be turned after the fingers 78 have engaged with the pin 84, so that the fingers 13 may close on the sheet. This 75 spring also holds the fingers 78 in advance of the fingers 13 when the latter are being closed, so that the fingers 78 come to guiding position before the fingers 13 engage the sheet. The set screw 80 is provided to limit 80 the relative motion of the fingers 13 and 78. The fingers 78 are spaced apart on either side of the gage 16 and the wiper 48 works between them. As will be seen by an inspection of Figures 3 and 10, a sheet may 85 be forced with considerable pressure against the gage 16 and yet, by reason of the presence of the overguides 78, will not buckle to permit its edge to slide up the gage 16.

It will be understood that the gearing between the chain 31 and the cylinder 9 is such as to cause one complete reciprocation of the carriage for each sheet presented to the cylinder 9.

A sheet placed on the tapes 18 will be carried toward the cylinder 9. In most cases this sheet will be out of square; that is, one side of its front edge will be in advance of the other. When the edge of the sheet reaches the front stops 46, which at this time 90 will be moving toward the cylinder 9 but at a point somewhat distant therefrom, the tapes 18, moving at a speed greater than the stops 46, will move the sheet against the stops and straighten it, the advanced side of the sheet being held until the other side has reached its stop also. As the carriage starts forward, the blocks 55 and 68 are located laterally in the position shown in Figures 6 and 7, each block being moved away from 100 the center of the machine. The grippers 57—70 are open at this time, the rollers 60—73 running on low places on cams 67—75. This permits the sheet S to pass between the side gages 56 and 69, as shown 105 in Figures 6 and 7. As the carriage progresses toward the cylinder 9 with the sheet S pressing against the front stops 46, the rollers 63 and 74 pass along the cam bars 67 and 75 and the blocks 55 and 68 are closed 110 in toward the center of the machine, the block 55 positively by the cam 67 and the block 68 yieldingly by the spring 76. This brings the pins 56 and 69 against the edges of the sheet S, the pin 56 moving to gaging 115 position and the pin 69 serving to ensure the edge of the sheet S contacting with the pin 56. The open grippers 57 and 70 will serve to guide the edge of the sheet to the pins 56—69 if the side of the sheet should hang 120

125 130

lower than the tapes 18. When the sheet has thus been pressed against the gages 56 and 69, the rollers 60 and 73, travelling along the top of the cam bars 67 and 75, are moved 5 upward by passing to the high part of these cams, thus closing the grippers 57 and 70 securely on the sheet. The sheet is now held positively in side registered position, and at the same time the grippers 57 and 70 assist 10 in carrying the sheet toward the cylinder 9. Shortly after the grippers 57 and 70 close on the sheet, the stops 46 arrive at the position shown in Figure 3, the cylinder 9 being set so that its gage 16 will receive the sheet 15 from the stops 46. Since, in my preferred form, the stops 46 are moving at a greater speed than the surface of the cylinder 9, the stops 46 will pass the gages 16, leaving the sheet thereagainst. To ensure absolute 20 accuracy in the final front registration of the sheet, the arm 48 is now moved by the cam 52 to engage the surface of the sheet close to its front edge and wipe it forwardly against the gage 16, the fingers 78 acting as over- 25 guides to prevent the sheet from rising up along the face of the gage 16. While this wiping action is taking place, the sheet is still held by the grippers 57 and 70 which are moving at a greater speed than the gage 30 16. This insures the edge of the sheet being against the gage 16, even without the action of the arm 48. As soon as the wiping action 35 of the arm 48 has been completed, the grippers 13 close on the sheet in the usual manner, the side grippers 57 and 70 releasing the sheet to allow it to be taken by the cylinder 9. This opening of the side grippers is caused by the lifting of the side frames 24 through the action of the rollers 41 on the 40 cam 43, which brings about the changes shown more clearly by a comparison of Figures 6 and 8. The lifting of the side frames 24 raises the bar 54 and with it the block 55. The roller 60, being on the top of the cam 45 bar 67, is held thereagainst by the spring 61 which opens the gripper 57 as the block 55 rises. If a more rapid opening of the grippers is desired, the cam bars 67 and 75 may be provided with depressions at the proper 50 points, so that the rollers 60 and 73 will run down the cams when the grippers are to be opened. After the sheet is taken by the grippers 13, the carriage is brought to rest by the connection 30' between the rod 30 and 55 the chain 31 passing around the sprockets 32, as shown particularly in Figure 1. The carriage then returns to its original position in a plane above that in which it approaches the cylinder 9, this causing the 60 stops 46 to clear the cylinder and not injure the sheet held by the grippers 13. For a similar reason, the before described structure of the cam 52 is provided so that the arm 48 will not be caused to damage the sheet on the 65 return stroke of the carriage.

It will be understood that the various stops, wipers, and gages are arranged to be shifted sidewise across the machine so that they may be brought into proper position for any width of sheet.

70

In locating the position of the stops 46, care is taken to make them coincide as nearly as possible with the position of the front stop 16 at the time that the sheet S is transferred from the one to the other. It will be understood that the stops 46 are in themselves registering members and if set with great care would give an approximately correct register to the sheet. Because of the defects inherent in all mechanism, however, there is always a possibility that, even though the sheet is properly registered against the stops 46, it will not be registered properly with the cylinder 9. This is particularly true in a reciprocating device such 85 as I have shown, in which the position of the devices at any given period of the cycle of operation may be influenced by the speed of working, an increase of speed setting up additional strains in the mechanism which 90 tend to cause the carriage to overthrow its stroke. By providing stops 16 on the cylinder 9, this difficulty is overcome, since the relation between the carriage and the cylinder may be varied considerably without 95 effecting the final register of the sheet on the cylinder 9.

90

It will be obvious that means for carrying out my invention may be varied widely from the specific device which I have chosen for purposes of illustration. My device for preliminary and final front registry may be used independently of the side registry and may be used in connection with any form of sheet carrier. Similarly, my method of obtaining side registry and holding the sheet in this registry may be used with devices other than the ones which I have illustrated for obtaining the front registry of the sheet.

100

The arrangement of the mechanism for giving the sheet side registry and for maintaining it in side register may be widely varied. It is possible to use only one gripper instead of the two which I have shown. Devices other than the yieldingly mounted 110 pin 69 may be used to position the sheet against the gage 56. For instance, a roller adjacent the gage 56 may be used to draw the sheet thereagainst and this form will be useful when very thin paper is being 120 handled. At the same time, such a roller could be locked to hold the sheet in side registry, thus dispensing with the side grippers. It is possible also to omit the lateral motion of the gage 56 and its supporting 125 block 55, though I find it preferable to give the gage this motion, so that a sheet can pass the gage without interference. It is also possible to mount the side gage and the mechanism for moving the sheet thereagainst 130

130

so that they do not travel with the sheet.

Some of the features of my invention are in the nature of refinements and may be omitted if found desirable. For instance, 5 the wiper 48 and the overguides 78 may be omitted and fixed overguides instead of the movable ones may be used. For many purposes, a carriage other than the reciprocating one which I have illustrated, might be used, 10 such, for instance, as a continuously rotat- ing chain carrying the various bars and gages. The relative speeds of the carriages, tapes 18 and cylinder 9 may be greatly varied, it being possible to move the car- riage at the same speed as the cylinder. The 15 tapes 18 must move faster than the stops 46, however, to properly square the sheet.

Having now described my invention, what I claim as new and desire to secure by Let- 20 ters Patent is as follows:

1. A continuously moving front gage, a moving front stop, means to support and move a sheet against said stop and means to support and move said stop toward and 25 past said gage while the sheet is against said stop.

2. A moving sheet supporting carrier, a sheet front gage toward which sheets are moved by said carrier, means to give a sheet 30 on said carrier a preliminary front registry and to present it to said front gage while so registered and means to give the sheet final front register against said gage.

3. A sheet carrier having a sheet front 35 gage thereon, a sheet conveyer arranged to carry sheets toward said carrier and said gage, a sheet stop movable in the path of a sheet on said conveyer at a speed lower than that of the sheet and means to move 40 said stop past said gage while the sheet is positioned against said stop.

4. A moving front gage, a movable front stop, means to position a sheet against said stop and means to support and move said 45 stop past said gage at a speed greater than that of said gage.

5. A sheet carrier having a sheet front gage thereon, a movable front stop, means to position a sheet against said stop and 50 means to support and move said stop past said gage at a speed greater than that of said carrier.

6. A moving front gage, a pair of movable front stops, means to move a sheet against said stops at a speed greater than that of said stops, to square the sheet, and means to support and move said stops past said gage at a speed greater than that of said gage.

7. A sheet carrier having a sheet gage 60 thereon, a sheet stop and means to support and move said stop past said gage at a speed greater than that of said gage.

8. A sheet carrier, a sheet stop, a carriage to support said stop, means to reciprocate 65 said carriage to move said stop back and

forth past the feeding point of said carrier and means to alter the position of said car- riage to cause said stop to pass said feeding point at one level and return at another level.

9. A sheet carrier having a sheet front gage thereon, a carriage and means to sup- port and move it toward and away from said carrier, a pair of sheet front stops on said carriage, arranged to pass said front gage 70 while a sheet is against said stops, means to move a sheet against said stops to square the sheet while said stops are moving toward said carrier and means to move said stops out of the path of the sheet.

10. A sheet carrier having a sheet front gage thereon, a carriage and means to sup- port and move it toward said carrier, a pair 75 of sheet front stops on said carriage, means to move a sheet against said stops to square it, and means on said carriage to move said sheet against said front gage.

11. A sheet front gage, a sheet side gage, means to position a sheet against said side gage, means to hold the sheet in fixed rela- 80 tion to said side gage and means to position the sheet against said front gage while the sheet is so held to said side gage.

12. A sheet front gage, a sheet side gage, mechanism constructed and arranged to po- 85 sition a sheet against said side gage and hold it in fixed relation to said gage and means to position the sheet against said front gage while the sheet is so held to said side gage.

13. Means to support and move a sheet in 100 a predetermined direction, means to give a sheet a preliminary front registry, means to give the sheet a final side registry and means to give the sheet a final front registry, said means being arranged to operate successively 105 in the order named and while the sheet is moving in said direction under control of said moving means.

14. A sheet front gage, a sheet front stop, means to move a sheet against said stop, 110 means to give a sheet side registry while it is positioned against said front stop and means to hold the sheet in side registry and to move it against said gage.

15. A moving front gage, a moving front 115 stop, a moving side gage, said stop and gages all moving in the same general direc- tion, means to move a sheet against said stop, means to move the sheet against said side gage and means to move the sheet against 120 said front gage.

16. A moving front gage, a moving front stop, a moving side gage, said stop and gages all moving in the same general direc- 125 tion, means to move the sheet against said side gage and mechanism constructed and arranged to move a sheet against said stop and against said front gage.

17. A moving sheet carrier having a sheet front gage thereon, means to support and 130

move a sheet toward said carrier, mechanism constructed and arranged to give a sheet a preliminary front registry and a final side registry while moving toward said gage 5 and means to give the sheet a final front registry against said gage.

18. A sheet front gage, a sheet side gage, means to move a sheet against said side gage to position it laterally and means to hold the side edge of the sheet in fixed relation to said side gage when so positioned and to move the sheet against said front gage.

19. A sheet front gage, a sheet side gage, means to move a sheet against said side gage 15 to position it laterally and a gripper constructed and arranged to engage the sheet while it is against said side gage and means to support and move said gripper toward said front gage.

20. A sheet front gage, a sheet side gage, means to move a sheet against said side gage to position it laterally and a pair of grippers constructed and arranged to engage the sides of the sheet while it is against said 25 side gage and means to support and move said grippers toward said front gage.

21. A sheet front gage, a sheet side gage, means to move a sheet against said side gage to position it laterally and mechanism constructed and arranged to engage the sides of the sheet fixedly while it is against said gage to hold the side edge of the sheet in fixed relation to said side gage and to move said sheet toward said front gage.

22. A sheet front gage, a sheet side gage, a support for said side gage, a gripper on said support, adapted to grasp a sheet positioned against said side gage, means to move a sheet toward said side gage, means to close said gripper and means to move said support toward said front gage.

23. A sheet front gage, means to support and move a sheet toward said front gage, a sheet side gage, a support for said side gage, a gripper on said support, adapted to grasp a sheet positioned against said side gage, means to position a sheet against said side gage while the sheet is moving toward said front gage, means to close said gripper and means to move said support toward said front gage.

24. A sheet front gage, a sheet side gage, means to hold the side edge of the sheet in fixed relation to said side gage and means to position the front edge of the sheet against said front gage while the sheet is so held.

25. A sheet front gage, a sheet front stop, a sheet carrier adapted to move a sheet against said stop and against said gage and mechanism constructed and arranged to support said stop and to move it back and forth past said gage, passing in one direction, when the sheet is positioned against said stop, close to the point of contact between said gage and

the sheet on said carrier and in the opposite direction above such point.

26. A pair of moving front stops, means to move a sheet against said stops at a speed greater than that of said stops, to square the sheet, means to give the sheet side registry after it is squared and while it is moving, means to give the sheet front registry after said side registration and means to hold the sheet in side registration while the front registry is being given.

27. A pair of moving front stops, means to move a sheet against said stops at a speed greater than that of said stops, to square the sheet, means to give the sheet side registry after it is squared and while it is moving, means to engage and hold the sheet in registry while it is moving and means to give the sheet front registration while it is so held.

28. A reciprocating carriage, a sheet gripper thereon, a cam roller connected to said gripper, a fixed cam arranged to co-operate with said roller to close said gripper as said carriage moves in one direction and means to move said carriage in a direction at 85 right angles to its path of reciprocation, to permit said gripper to open while said roller is in contact with said cam.

29. A sheet support, a sheet side gage, means to support and move said gage in a 95 direction substantially parallel with the edge of a sheet on said support, means to move said gage toward said edge and means on said gage supporting and moving means and independent of said support to engage and hold unyieldingly a sheet positioned against 100 said gage.

30. A sheet support, a pair of sheet side gages, means to support and move said gages in a direction substantially parallel with the edges of a sheet on said support, means to move said gages, one yieldingly and one positively, toward said edges and means on said gage supporting and moving means and independent of said support to hold unyieldingly a sheet positioned against said gages.

31. A sheet gripper, a traveling carriage therefor, means to close said gripper while said carriage is moving, means to shift said carriage at right angles to its main direction of travel and connections between said gripper and said closing means constructed and arranged to permit said gripper to be opened when said carriage is shifted.

32. A sheet gripper, a traveling carriage therefor, a fixed cam parallel to the main direction of travel of said carriage, a cam roller connected to said gripper and moving on that side of said cam farthest from said carriage, means to move said carriage towards said cam at right angles to its main direction of travel, said parts being constructed and arranged to permit said

gripper to be opened when said carriage moves towards said cam.

33. A sheet carrier having a sheet front gage thereon, a sheet support adjacent said carrier, a carriage and means to support and reciprocate it toward and away from said carrier, a sheet side gage on said carriage, means to position a sheet on said support against said side gage and means on said carriage to engage and hold the sheet so positioned to move it towards said front gage with said carrier.

34. A sheet carrier, having a sheet front gage thereon, a sheet support adjacent said carrier, a carriage and means to support and reciprocate it toward and away from said carrier, a sheet side gage on said carriage, means to position a sheet on said support against said side gage, means on said carriage to engage and hold the sheet so positioned to move it toward said front gage with said carrier, and means to cause said engaging means to release the sheet before said carriage reverses its motion.

35. A sheet carrier, a sheet support adjacent thereto, a carriage and means to support and move it toward and away from said carrier, a pair of side gages and a pair of side grippers on said carriage and means to move said side gages against a sheet on said support and to close said grippers on the sheet while said carriage is moving toward said carrier.

36. A sheet support, a moving front gage, means to give a sheet side registry on said

support, means to hold the sheet fixedly in side registry and move it toward said front gage, and means to engage the head of the sheet and move the edge thereof against said front gage while the sheet is so held. 40

37. A front gage, a front stop, mechanism constructed and arranged to move a sheet first against said stop and then against said gage, and mechanism to move said stop and said gage in the direction of motion of the 45 sheet and to move said stop past said gage when the sheet is positioned against said stop.

38. A sheet support, means to give a sheet on said support a preliminary front registry, additional means to maintain the sheet in such registry, and means to give the sheet a final front registry. 50

39. A moving sheet support, means to give a sheet moving on said support a preliminary front registry, means moving with the sheet adapted to give the sheet a side registry and additional means adapted to give the sheet a final front registry. 55

40. A moving sheet support, means to give 60 a sheet moving with said support a preliminary front registry, means to give the sheet a side registry, and additional means adapted to give the sheet a final front registry.

JOSEPH WHITE.
